WHEEL

Dann T. Deaver, Mount Clemens, Mich., assignor to
Motor Wheel Corporation, Lansing, Mich., a corpora-
tion of Michigan

Filed Oct. 16, 1963, Ser. No. 76,996

Term of patent 14 years

(Cl. D14—30)

FIG. 1

FIG. 2

FIG. 3

FIG. 4

FIG. 1 is a side elevational view of a wheel showing my new design.

FIG. 2 is a sectional view taken on line 2—2 of FIG. 1.

FIG. 3 is a sectional view taken on line 3—3 of FIG. 1.

FIG. 4 is a sectional view taken on line 4—4 of FIG. 1.

The essential features of my new design reside in the full line portion of the drawing.

I claim:

The ornamental design for a wheel, substantially as shown and described.
